UNITED STATES PATENT OFFICE

155,263

DESIGN FOR A FRAME FOR A MULTINEEDLE SEWING MACHINE

Gustav A. Boettcher, Jackson Heights, N. Y.

Application August 21, 1946, Serial No. 132,683

Term of patent 7 years

(Cl. D70—1)

To all whom it may concern:

Be it known that I, Gustav A. Boettcher, a citizen of the United States, residing at Jackson Heights, in the county of Queens, in the city and State of New York, have invented a new, original, and ornamental Design for a Frame for a Multi-needle Sewing Machine, of which the following is a specification, reference being had to the accompanying drawing, forming part thereof.

In the drawing:

Fig. 1 is a top plan view of a frame for a multi-needle sewing machine, showing my new design;

Fig. 2 is a side elevation of the same frame;

Fig. 3 is a longitudinal section of the frame taken on line 3—3 in Fig. 1;

Fig. 4 is an end elevation as seen from the left in Fig. 2; while Fig. 5 is another end elevation as seen from the right in Fig. 2.

The characteristic features of my design for

the frame disclosed reside in the end supports having the configuration shown.

I claim:

The ornamental design for a frame for a multi-needle sewing machine, substantially as shown and described.

GUSTAV A. BOETTCHER.
